SIDE DRAWING WINDING DEVICE

William Charles Hanse, Philadelphia, Pa., assignor to American Viscose Corporation, Wilmington, Del., a corporation of Delaware

Application May 12, 1948, Serial No. 26,662

5 Claims. (Cl. 242—18)

1

This invention relates to apparatus for unwinding a strand and particularly to apparatus for unwinding packages of filamentary material from which the strand is preferably removed in a direction tangential to the outer periphery of the package.

In manufacturing rayon yarn, cakes of the yarn as taken from the spinning machine are subjected to various treatments including washing and drying. During such processing, the cakes become thoroughly loosened and limp and the strands thereof often become curly, snarled, tangled or otherwise disarranged. These cakes are normally placed on a package-building or twisting machine for unwinding and reforming the strand into more compact and accurately formed packages within the requirements of weavers, knitters, dyers and the like. In these machines, the simplest and most common arrangement for withdrawing the strand from the cake is to support it on a non-rotatable holder and draw the strand or yarn through a guide placed over the center of the end or top of the cake. By this arrangement the strand is removed from the cake in a direction considerably at variance with the direction taken by the helical windings in which the strand occurs on or within the cake.

Irregularities in strand deposition while forming the cake, or the subsequent processing thereof, may cause the strand to be tufted or snarled within the cake. Although measurable draft is required for withdrawal of the strand laterally of the direction in which it occurs on the cake, the draft required is greatly intensified if for any reason there are interferences with the departure of the strand from the cake such as tangling, snarling and the like. Added to the tension produced by a tangle or snarl is the additional force required to overcome friction produced when the strand tightens against the lateral surface and edge of the cake. Very frequently, the strand breaks under such conditions and the winding or twisting machine is inoperative until the strand is again laced through the machine. Very often the forming of cakes or the processing thereof is such that a high percentage of the cakes cannot be unwound on conventional repackaging or twisting machinery and are subsequently rejected as waste.

As a principal object of the invention therefore, an improved apparatus is provided for unwinding strand packages by which the strand is subjected to less draft than applied by conventional unwinding devices, and a high percentage of strand packages such as rayon cakes produced by the

2

viscose method may be successfully unwound.

Another object is to provide an inexpensive, simple, trouble-free unwinding apparatus which may be readily installed on any machine on which it is desired to unwind strand packages. Other objects, advantages and features of the invention will be apparent in the following description of the invention and the drawing.

In the drawing illustrative of the invention:

10 Fig. 1 is an elevation partly in section of an unwinding device according to a preferred embodiment;

Fig. 2 is a side view of the supporting means for the apparatus shown in Fig. 1;

15 Fig. 3 is a sectional view of a modified supporting means;

Fig. 4 is a sectional view of another modification of a supporting means; and

Fig. 5 is an end elevation of a winding machine 20 showing supported thereon an unwinding device according to the invention and a brake means for the device.

Broadly the invention comprises an apparatus for rotatable and swingable support of a strand package and side draft means for withdrawing a strand therefrom. In order that a strand package may be quickly placed upon a package holder, the package holder is made quickly removable from a winding or an unwinding machine.

30 In Fig. 1 a package holding device is shown suspended by a member comprising rod or tube 6 from a supporting bracket 8. A strand package 10, such as a rayon cake is shown in place on the package holder 5, sitting on the upper flat 35 surface of an annular member or platform 11. The inner surface of the strand material is supported by a cake cover 12 (inserted into the cake before placement thereon on the package support 5) reinforced by cuff 13 of a material such as 40 cardboard. In the usual manufacturing operations, a cover 12 is placed over a rayon cake prior to the washing and drying thereof which precedes unwinding in order to protect the yarn and to keep it from becoming tangled and otherwise disarranged. The cover 12, before placement on the cake, is normally a sleeve-like piece of cloth. It is inserted through the central opening of the cake and the ends of the cover are then spread over the ends of and around the sides of the cake.

45 The ends of the cover 12 are then removed from the sides of the cake and folded over the annular ends of the cuff 13 and along its inner surface to form the arrangement shown in Fig. 1.

50 The filamentary package 10 is maintained in an expanded and extended condition favorable

55

to strand unwinding by any conventional apparatus adapted for frictionally engaging the inner periphery of a strand package and centering it on the holder, such as, spring members 14 which press against interior surface cake cover 12. The springs 14 are attached at the collar 15 slidably mounted on the shaft 6. The springs may also be attached to the plate 11, or if desired, the lower ends thereof may be retained in short radial slots (not shown) in the plate 11 for limiting the movement of their lower extremities.

As an essential feature of the invention, the package holder is supported by a member thereof such as the rod 6 extending centrally above the region occupied by the strand package 10 and joining swivably and rotatably with a stationary portion of a winding machine in order that the package holder and the package may have pendulous and rotative freedom while the strand is withdrawn in a direction tangential to the surface thereof. It is desired that the package holder be able to yield in pendulous movement to sudden increases in tension imposed upon the strand during an unwinding operation, which might result in breaking the strand as by sudden jerking. As a preferred means for obtaining such pendulous and rotative freedom, the bracket 8 is provided with a horizontally extending portion 16 having a slot 17 extending inwardly from a side of the portion 16. The slot 17 is sufficiently wide so that the rod 6 may extend through it and have sufficient clearance for universal pivoting within the slot when the package holder undergoes swinging motion.

Support of the package holder on the portion 16 of bracket 8 is obtained through a cone-shaped washer 22 fitting loosely about the shaft or tube 6 and bearing on the sides of groove 17, and a non-slip collar 19 bearing on the washer 22. The collar 19 is secured to the shaft 6 by such means as a set screw 20. Since the washer 22 overlaps upper surfaces of the support portion 16 may readily shift or tilt along the edges of the groove 17, and the collar 19 may tilt within the washer 22 within the limits of movement permitted the shaft 6 within the large aperture 24 of the washer 22, the holder 5 may swing freely in any direction and rotate about the axis of shaft 6. The assembly comprising the washer 22, the collar 19, and the shaft 6 is prevented from leaving the slot 17 during withdrawing of the strand, by a ridged portion 26 of the bracket.

Considerable inertia is acquired by the strand package 10 and the holder 5 therefor as a consequence of the rotational velocity developed during a normal strand-withdrawing operation. There is considerable tendency for the holder-package assembly to maintain its rotation after the stopping of the withdrawal means, such as a winding device. In order that the rotation and the package support may be quickly halted to prevent tangling of the yarn, a brake means is provided comprising a brake shoe 28 which may be pressed against a radially extending downwardly-facing frictional surface of the plate 11, and a brake-rod and lever system comprising rod 29, pivot lever 33, and rod 34 extending to and connecting with the stopping lever 30 of a conventional winding machine shown in Fig. 5. Movement of the lever 30 anti-clockwise (as viewed in Fig. 5) to a stopping position is transferred through the brake rod 29 to the shoe 28 and causes it to rise and to make frictional contact with the plate 11. The brake is released

when the lever 30 is moved back to operating position to again start the winding machine. Any lever system responsive to movement of the lever 30 whereby the system operates a braking element such as brake shoe 28 may be used in lieu of the lever chain shown. For example a highly satisfactory alternative means (not shown) for transmitting such movement is a Bowden cable.

In Fig. 5 a cake 10 is shown supported on a device according to the invention, such as illustrated in Fig. 1, said device being mounted on a conventional cone winding machine as shown in Fig. 5. To give additional protection against shock or sudden tension which might be encountered in unwinding severely tangled cakes, the strand 32 is led over a fixed guide pulley 35 and a dancer roll 36 before passing through a conventional baffle type tension device 37. For example, when a winding machine such as illustrated in Fig. 5 is started, there is appreciable tension developed in the strand 32 as a result of static inertia stored in the holder 5 before it reaches normal unwinding speed required by the machine. Dancer roll 36 is provided with appreciable range of movement in a direction that is lateral to the direction of lengthwise advancement of the strand, and serves admirably and satisfactorily for preventing excessive variations in the tension on the strand leaving the package 10. As shown, the holder is open along the periphery of the package 10 carried by the holder 5 to enable the strand to pass to the guide pulley 35. The dancer roll 36 may be weighted and supported by the strand as shown in Fig. 5 or it may be springably or resiliently linked with stationary support means, not shown, to apply a force to the strand that is lateral with respect to its longitudinal direction of movement.

As an alternative means for supporting the package holder according to the invention, a "ball-and-socket" type joint is illustrated in Fig. 3 in which an element 40 is fixed on shaft 6 by any suitable means such as set screw 41. Element 40 is the ball portion of the joint and has an approximately semispheroidal outer surface which fits within a complementary socket surface within the supporting member 16a, which may be a portion of such a fitting as bracket 8 shown in Fig. 1. Portions of the apparatus shown in Fig. 3, having similar function and construction to those in Fig. 2 are given the same numeral except that the letter "a" is added.

Still another means for swingably and rotatively supporting the holder 5 is shown in Fig. 4 wherein the shaft 6 of the holder 5 is fixed within the end of a universal coupling such as tubular flexible coupling 43 which may be formed of a resilient elastic material such as a vulcanized rubber and fabric composition. The shaft 6 is secured within the end of the coupling by means of a clamp 44. The upper end of the coupling is secured by a similar clamp 46 about the end of a shaft 47 projecting through the roller thrust bearing 48. The shaft 47 may be loosely supported within the bearing 48 but is preferably prevented from contacting the walls of the aperture through the lower race 49. Axial movement of the shaft 47 is prevented by a collar fixed thereto by a means such as set-screw 51. The whole assembly may be supported on a fixture similar to the bracket 8 of Fig. 1 so that instant removal of the assembly is facilitated by lateral movement of the shaft 47 through a slot 45 in the manner in which the package support shaft 65 of the other embodiments herein described are

removed from respective supporting brackets. In the type of support shown in Fig. 4, a coupling such as the coupling 43 resiliently resists any swing of the package holder 5. The holder swings out its normal operating axis at times when the tension in the strand being withdrawn is increased. Inertia and gravity forces which maintain the holder in normal axial alignment are aided by the tendency of a resilient coupling of the type shown in Fig. 4 to remain in alignment when the holder is pulled to one side.

By the arrangements shown, strand packages such as rayon cakes which are so tangled or snarled as to be unsuitable for winding on conventional unwinding equipment may be readily unwound on the apparatus herein described as a result of eliminating the excessive frictional effects developed as when yarn is withdrawn from a cake through a guide located axially beyond one end of the cake.

While preferred embodiments have been shown, it is to be understood that changes and variations may be made without departing from the spirit and scope of the invention as defined by the appended claims.

I claim:

1. In apparatus for unwinding an annular package; a strand drawing means; a control for the drawing means that is movable between a position for stopping said means and a position for operating said means; a stationary support; a package holder having an axis about which a strand package may be supported and the holder rotated comprising a package-supporting platform and a member extending lengthwise of the axis upwardly and centrally from the platform and adapted to extend and be inserted through the hollow portion of a package, an upper portion of the member being connected to the support in swivable, rotatable, and readily separable relationship to provide pendulous suspension of the holder and rotatability thereof about said axis, said holder being open with respect to the periphery of a package supported thereon and having a frictional surface disposed generally concentrically with the axis; frictional means connected with the control and supported adjacent the frictional surface for movements into and out of engagement with said frictional surface in response to movements of the control into and out of, respectively, said stopping position; and means in spaced lateral relationship with the holder for guiding the strand.

2. In apparatus as defined in claim 1, said frictional surface constituting a downwardly-facing surface of the platform.

3. In apparatus for unwinding an annular package; a package building spindle; a control for the spindle that is movable between a position for stopping a spindle and a position for operating the spindle; a stationary support; a package holder having an axis about which the strand package may be supported and the holder rotated comprising a package-supporting platform and a member extending lengthwise of the axis upwardly and centrally from the platform and adapted to extend and be inserted through the hollow portion of the package, an upper portion of the member being connected to the support in swivable, rotatable, and readily separable relationship to provide pendulous suspension of the holder and rotatability thereof about said axis, said holder being open within the region surrounding the periphery of a package sup-

ported thereon and having a frictional surface disposed generally concentrically with the axis; frictional means connected with the control and supported adjacent the frictional surface for movements into and out of engagement with said frictional surface in response to movements of the control into and out of, respectively, said stopping position; means in spaced lateral relationship with the holder for guiding the strand therefrom; and resilient means for engaging the strand in a direction that is lateral with respect to its longitudinal direction of movement in passing from said guiding means to the spindle.

4. In apparatus for unwinding an annular strand package; a package-building spindle; a control for the spindle that is movable between a position for stopping the spindle and a position for operating the spindle comprising a package-supporting platform and a member extending lengthwise of the axis upwardly and centrally from the platform and adapted to extend through the hollow portion of the package; a stationary support; a package holder having an axis about which the strand package may be supported and the holder rotated, said holder being connected to the support in swivable and rotatable relationship therewith to provide suspension of the holder and rotation thereof about said axis, the holder being open about the periphery of a package supported thereon and having a frictional surface disposed concentrically with the axis, the support and the member being connected by overlapping portions of the support and the member interrelated for instant coupling and uncoupling; and frictional means connected with the control and supported adjacent the frictional surface for movements into and out of engagement with said frictional surface in response to movements of the control into or out of, respectively, said stopping position; the holder and the frictional means being independently supported within the apparatus whereby the holder may be instantly detached from the support without interference with the frictional means for reloading of a package thereonto.

5. In apparatus for unwinding an annular strand package; means for drawing the strand; a control for the drawing means that is movable between a position for stopping the means and a position for operating the means; a stationary support; a package holder having an axis about which a strand package may be supported and the holder rotated comprising a package-supporting platform and a member extending lengthwise of the axis upwardly and centrally from the platform and adapted to extend and be inserted through the hollow portion of the package, an upper portion of the member being connected to the support in swivable, rotatable, and readily separable relationship therewith to provide pendulous suspension of the holder and rotatability thereof about said axis, said holder being open within a region disposed radially exteriorly of a package supported thereon and having a lower radially extending downwardly-facing frictional surface disposed concentrically with the axis; a frictional member; means connected with the control for supporting the frictional member for reciprocation along an upwardly-extending path, such path being disposed to carry the member into and out of engagement with the frictional surface, said member being moved by the control into engagement with the frictional surface in response to movement of the control to the stop-

ping position; means in spaced lateral relationship with the holder; a dancer roll for engaging the strand along its path of advancement between the guide means and the drawing means, said dancer roll being resiliently supported for movement in a direction extending laterally away from said path for eliminating slack in the strand.
